UNITED STATES PATENT OFFICE.

CHARLES B. BARKER, OF BROOKLYN, NEW YORK.

DESIGN FOR A PICTURE-FRAME.

SPECIFICATION forming part of Design No. 24,986, dated December 17, 1895.

Application filed October 13, 1893. Serial No. 488,097. Term of patent 3½ years.

To all whom it may concern:

Be it known that I, CHARLES B. BARKER, a citizen of the United States, residing in Brooklyn, county of Kings, and State of New York, have invented and produced a new and original Design for Picture-Frames, of which the following is a specification, reference being had to the accompanying drawing, forming a part thereof.

10 The figure represents a face view of a frame, showing my design.

The leading feature of my design consists in the representation of a horseshoe forming the outline of the frame, having an inner heart-shaped border-line.

15 *a* is the horseshoe forming the outline of the frame, and *b* the inner heart-shaped border-line of the same which forms the outline of the picture-opening.

The design also consists in the decoration 20 of the frame, which decoration consists in the representation of a bow-knot *c* arranged at one end of the frame and a wishbone *d* at the opposite end. Flower figures *e* and *f*, representing the four-leaf clover and the forget-me-not, respectively, are arranged at each side of the bow-knot *c* at the upper end of the frame, and also at the lower end of the latter, as shown.

25 What I claim is—

The design for a picture frame, substantially as herein shown and described.

CHARLES B. BARKER.
